UNITED STATES PATENT OFFICE

PHILLIP SOCKETTE, OF LOS ANGELES, CALIFORNIA, ASSIGNOR TO ATLAS LEATHER PRODUCTS CORPORATION, OF LOS ANGELES, CALIFORNIA, A CORPORATION OF CALIFORNIA

DESIGN FOR A COMBINED KEY CONTAINER AND ARTICLE HOLDER

Application filed December 7, 1931. Serial No. 41,993. Term of patent 7 years.

To all whom it may concern:

Be it known that I, PHILLIP SOCKETTE, a citizen of the United States, residing at Los Angeles, in the county of Los Angeles and State of California, have invented a new, original, and ornamental Design for a Combined Key Container and Article Holder, of which the following is a specification, reference being had to the accompanying drawings, forming a part thereof.

Figure 1 is a perspective view of a combined key container and article holder showing my new design and in closed position.

Fig. 2 is a front elevation of the same with the key container flap open.

Fig. 3 is a top plan view of the same with the key container flap in closed position.

I claim:

The ornamental design for a combined key container and article holder, as shown.

Signed at Los Angeles, in the county of Los Angeles and State of California, this 28th day of November, 1931.

PHILLIP SOCKETTE.
